NEEDLE MOTION FOR LOOMS

Oscar V. Payne, Leicester, Mass., assignor to Crompton & Knowles Loom Works, Worcester, Mass., a corporation of Massachusetts

Application September 2, 1939, Serial No. 293,184

15 Claims. (Cl. 139—123)

This invention relates to improvements in weft needle mechanisms more particularly for wide looms and it is the general object of the invention to provide light weight actuating mechanism for needles capable of attaining high speeds.

It has been customary heretofore to drive the needles of Axminster looms by mechanism including heavy gears and a rotatable drum moved by a segment gear. The weight of these driving parts has interfered with efforts to increase loom speed and it is an important object of my present invention to replace these heavy parts by a system of stationary and movable pulleys around which is trained a cable connected to the needle carriage. The movable sheaves may be mounted on a single axis and the arrangement of the parts is such that a comparatively small motion on the part of the axis is multiplied several times to provide sufficient sweep for the needle.

It is a further object of my invention to arrange the sheaves and the cable so that one-half of the movable sheaves can be on one side of the driving lever therefor while the other half is on the opposite side, thereby equalizing the strains placed upon the driving lever and relieving it of any tendency to twist.

It is a further object of my present invention to employ a cable the ends of which are fixed relatively to each other and the intermediate part of which is connected to a sliding needle carriage, together with a set of movable sheaves so related to the moving cable that the intermediate part of the latter will be caused to move along the needle rail when the sheaves move to cause a paying-out motion of one end of the cable which is just compensated for by a shortening of the other end of the cable. This result may be accomplished by leading the cable from a fixed anchor around half of the movable pulleys and half of the stationary pulleys and then connect it to the needle carriage, the remainder of the cable extending from the carriage to be trained around the remaining stationary and removable sheaves and then attached to another fixed anchor. The cable ends, however, need not be stationary but can move with the axis, if desired.

It is a further object of my present invention to select a sheave of such diameter and space the movable pulleys from the stationary pulleys at such distances that no part of the cable is ever required to engage more than one sheave.

Still another object of my invention is to arrange the sheaves and cable in such a way that

the curves in the latter due to the sheaves are all in the same direction so that the cable is never required to reverse the direction of its curvature. In this way I avoid subjecting the cable to alternating strains in opposite directions and hence prolong its life.

The pulleys for the cable would rotate at relatively high speeds if they turned at a rate proportional to that of the needle carriage, but by using the arrangement described hereinafter the pulleys turn at comparatively low speeds, thereby reducing wear and prolonging the life of both the pulleys and cable.

In the operation of a needle motion it is desirable to produce a retardation in its movement when out of the shed to give time for the lay to beat up. It is another object of my present invention to drive the needle by mechanism which will require more time in reversing needle direction when the needle is out of the shed than is required when the needle is entirely in the shed. This general result I obtain hereinafter by a crank and a relatively short connector the effect of which is to cause a comparatively quick reversal of the needle motion when the needle is entirely in the shed but cause a comparatively slow reversal when the needle is out of the shed. I do not wish, however, to be limited to the particular means shown for accomplishing this result.

With these and other objects in view which will occur as the description proceeds, my invention resides in the combination and arrangement of parts hereinafter described and set forth.

In the accompanying drawings, wherein a convenient embodiment of my invention is set forth: Fig. 1 shows a front elevation of the preferred form of my needle mechanism as it would appear at the right hand end of a loom with the needle in the shed.

Fig. 2 is a plan view of the direction of arrow 2, Fig. 1.

Fig. 3 and Fig. 4 are end elevations taken in the direction of arrows 3 and 4, respectively, Fig. 1.

Fig. 5 is a vertical section on line 5—5 of Fig. 1.

Fig. 6 is a diagrammatic view showing the movable sheave actuating mechanism in three different positions.

Fig. 7 is a detail end elevation in the direction of arrow 1, Fig. 1, showing the movable sheave actuating lever.

Fig. 8 is a detail of the head on one end of the cable, and

Fig. 9 is a diagrammatic elevation showing a modified form of the invention wherein the ends of the cable move with the movable pulleys.

In the accompanying drawings, I have shown the needle motion without illustrating the loom with which it would be used. It is to be understood that the loom not shown will have shed forming mechanism to separate the warp threads for entry of the needle and will have a reed to beat up the filling after the needle has been moved out of the shed. Furthermore, the needle will operate with a stationary supply of weft and will therefore lay a double pick of filling and when used in connection with Axminster looms there will be a selvage shuttle at the side of the loom opposite the needle mechanism. Since these parts are well-known they are omitted from the drawings, but it is to be understood that the loom proper will be located at the left of the structure shown in Fig. 1 and that the needle will be projected into the shed by a movement of the left.

Referring particularly to Figs. 1 and 2, I have shown a loomside 10 to which is attached a needle frame 11 supported by a base 12 and having a needle rail 13 slotted as at 14 to guide a needle carriage 15. A needle 16 is secured to the carriage and is adapted for reciprocating motions to the right and left as the carriage slides along the rail 13. The matter thus far described, except for structure supported by the needle frame 11, may be constructed as usual and of itself forms no part of my present invention. A carriage 15 is ordinarily attached to a cotton cable but I have modified it for attachment to a steel cable which I prefer to use instead of the cotton rope.

In carrying the preferred form of my invention into effect I provide a cable having its ends fixed and trained around two sets of movable pulleys located between two sets of stationary pulleys, one of the latter sets at each end of the rail. The carriage 15 is attached to the cable approximately at its mid point and is caused to slide along the rail when the movable pulleys are actuated by driving mechanism.

In order to carry this mode of operation into effect I provide a shaft 20 which preferably though not necessarily rotates at uniform speed to revolve a crank arm 21. The latter has pivotal connection at 22 to a link 23, the right end of which is pivoted as at 24 to a movable pulley actuating lever 25. The lower end of this lever carries a stud 26 to provide a pivotal connection for a link 27 pivoted to the frame at 28 and arranged to rise and fall as the crank arm rotates.

As shown in Fig. 7, the stud 26 is carried by a bearing foot 31 the upper part 32 of which extends along the lower end 33 of the lever 25. A key 34 on the bearing part 32 fits into a slot 35 in the lever end 33, and slots 36 afford a vertical adjustment for the foot 31 with respect to the pivot 24. By this construction I am able to vary the distance between the pivots 24 and 26 and therefore vary the stroke of the upper end of the lever. Bolts 37 passing through slots 36 hold the adjustment of the lever with respect to the foot, as suggested in Fig. 7.

A second link 38 is pivoted at its lower end to the lever to swing about axis 24 and at its upper end is pivoted as at 39 to a horn 40 on the needle frame 11. The links 27 and 38 provide a floating support for the lever 25 and the upper link requires the upper end of the lever

to move in a substantially horizontal line, the lower link 27 being movable in a vertical direction to compensate for the arcuate motion of the lever around its pivot 24 when swinging.

The upper end 45 of lever 25 carries a stud 46 fixed thereon and extending on both sides of the lever, as shown for instance in Fig. 5. This stud carries the movable pulleys all of which move together in a horizontal direction when the lever 25 rocks. The movable shaves are located on both sides of the lever, three being in front of and three behind the lever.

The inner end, or that part at the left of Figs. 1 and 2, of the needle frame 11 supports a bracket 47 having two horizontally adjustable fixed pulley bearing members 48 and having also a bearing 49 for another fixed pulley to be described presently. The outer end of the needle rail has secured thereto another bracket 50 provided with two horizontally adjustable fixed pulley bearing members 51 and having also another fixed pulley bearing 52 similar to bearing 49. A cable anchor 53 also horizontally adjustable in bracket 47 is attached as at 56 to one end of a cable C, while the other end of the cable is attached as at 57 to a second cable anchor 58 also horizontally adjustable in the bracket 50.

Returning now to a consideration of the pulleys, cable C extends from the anchor 53 and is trained over movable pulley 60 on stud 46 and then leads to the left to a fixed pulley 61 held by one of the bearings 48. The cable then leads to a second movable pulley 62 and again leads to the left around a second stationary pulley 63 on the other of the bearing members 48, after which the cable is led around a rear movable pulley 64. From the under side of pulley 64 the cable again leads to the left and is trained around a large pulley 65 movable about the fixed axis 49. From pulley 65 the cable extends to the needle carriage to be secured thereto and then continues along the needle rail to be trained around pulley 66 rotating on the fixed axis 64. The cable then leads to movable pulley 67 and then returns to the right to extend around pulley 68 on one of the fixed bearing members 51 and thence back to the left around another movable pulley 69. From the last named pulley the cable extends around pulley 70 at the right side of the mechanism held by the other of the fixed bearing members 51. From fixed pulley 70 the cable extends to the left around the last of the movable pulleys 71 and extends from the latter to the anchor 58.

The bearing members 48 and 51, and also the anchors 53 and 58 are longitudinally adjustable and held in their adjusted positions as indicated in Fig. 2 for the purpose of taking up any slack which may exist in the cable. It will be noted that the stresses on the lever 25 and stud 46 are equalized and that each of the right and left hand parts of the cable extend around one pulley on one side lever 25 and around two pulleys on the other side thereof. The cable is made of a number of wire strands twisted together and is made in two sections. Each end of each section may be fitted with a head 75, shown in Fig. 8 as having a bore 76 to receive the cable end and having an eye 77 for an attaching stud. After the cable is inserted into the bore the reduced end 78 of the head is subjected to pressure to cause the metal of the head to flow into the spaces between the cable strands. The pivots 56 and 57 are in effect pins to enter the eyes 77 of the heads, while the needle car-

riage 15 has studs 79 for the eyes of the adjustment heads.

In operation, the shaft 20 will rotate by mechanism not shown either with a uniform rotation or with an irregular rotation which retards the motion of crank 21 when the latter is to the left of the shaft 20. I have operated a needle motion with both types of rotation of shaft 20, but under both conditions the action of the pulleys and the cable will be very similar except where the crank arm is retarded as already mentioned the needle speed will be reduced when it is out of the shed. Assuming, however, that shaft 20 rotates uniformly and that the parts are in the position shown in Fig. 1 with the needle in the shed, corresponding to the dot and dash position of Fig. 6, the lever 25 will rock to the left by counter-clockwise rotation of shaft 20, and in doing so will carry the six movable pulleys which rotate on the stud 46. As these pulleys move to the left the distance between stud 46 and the axes of the fixed pulleys at the left of the mechanism decreases to shorten the length of the cable extending to the left from pulleys 60, 62 and 64. At the same time the distance between stud 46 and the fixed pulleys at the right of the mechanism increases by the same amount and therefore the length of cable between pulleys 67, 69 and 71 extending to the right is increased. The shortening resulting in that part of the cable extending to the left of the movable pulleys provides the increased length necessary for the lengthening part of the cable extending to the right of the movable hook, and that part of the cable extending between the large fixed pulleys 65 and 66 therefore moves to the right and carries the carriage 15 toward the pulley 66 to retract the needle 16 from the shed.

During this left hand motion of lever 25 the latter will pass from the dot and dash position of Fig. 6 through the full line position, at which time the needle is moving at its most rapid rate, and then passes on to the dotted position at the left of Fig. 6 which corresponds to the end of the needle retracting stroke.

As shaft 20 continues to rotate the lever 25 will start to move to the right and in doing so will cause the cable to have a motion the reverse of that already described and cause the carriage 15 to move to the left to insert the needle in the shed.

I have found that a needle motion constructed as set forth herein can be operated at a higher rate of speed than motions heretofore constructed due to the fact that the cable and movable pulley are comparatively light. I have shown six movable pulleys, and since each movable pulley either slackens or takes up, depending upon the direction of its motion, twice as much cable as the distance through which it moves, I am able to drive the needle through a distance six times the length of travel of stud 46 in a horizontal direction. In this connection I may state that it is the horizontal motion of stud 46 which is the effective component of its motion in causing movement of the cable, and it is for this reason that I use the suspension link 38 which in effect causes the stud 46 to move in a substantially horizontal line. I find also that by making the pulley of a composition material, such as a phenol-condensation product, they can be made thin and at the same time withstand wear as the cable moves along their grooves.

In the modified form of the invention shown

in Fig. 9, the fixed pulleys are indicated at 85 and the movable pulleys at 86. The actuating lever 87 has a stud 88 for pulleys 86 and also has provision for attachment with the ends of cable K. In this instance, the movement of the needle carriage is an odd factor of the movement of stud 88. If but one movable pulley is used for each side of the cable K the factor is three, and increases by two for each additional movable pulley. The unit of measure used in carpet work is the yard, referred to as 4/4. If the stroke of the levers 25 and 87 is 2/4, it is possible to build needle mechanisms in 2/4 steps without making radical changes in the structures described. The multiplying factor of six in the preferred form gives a needle motion for a 12/4 loom. If the width is to be 14/4, the additional 2/4 is obtained by attaching the cable end to the moving pulleys, as in the modified form, and adding an extra stationary pulley. The clearance at the near selvage, and the overthrow for the selvage shuttle can be obtained by a slight increase in the motion of the movable pulleys, and such variations as occur in these parts of the needle travel when the width of the loom is changed can be compensated for by adjustments described in connection with Fig. 7.

From the foregoing it will be seen that I have provided a simple form of needle mechanism including a cable which is trained around the intermediate movable and fixed end pulleys and wherein movement of the pulleys causes movement of the needle carriage attached to the cable. The extent of movement of the carriage can be varied by the number of movable pulleys employed and I do not wish necessarily to be limited to the exact relation of pulleys shown herein. It will also be seen that the lever 25 is suspended in such a way that the stud 46 moves in practically a horizontal line, hence all of the motion of the movable pulleys is available for causing motion of the needle carriage. Furthermore, the movable pulleys are not required to move peripherally at the high rate of the needle carriage, thus reducing wear both of themselves and the parts of the cable when contacting them. Also, as seen in Fig. 1, the cable curves always in the same direction and is not subject to reverse curves which would increase wear. Again, the mechanism is adaptable to widths of looms which vary by 2/4 merely by attaching the cable ends to the movable pulley support when widths are desired which are an odd factor of the movable pulley stroke. The driving shaft 20 rotates continuously, with either constant or variable speed, thereby eliminating the heavy gearing heretofore used to produce intermittent motion of the needle, and permitting the attainment of speeds higher than formerly. In both the preferred and modified form of the invention the cable ends are fixed with respect to each other whether actually stationary as in Fig. 1 or movable with the lever 87, and the anchorage for the cable ends, whatever its form, is the means which causes the carriage to reciprocate when the intermediate pulleys move as described. Further, the nature of the crank drive requires more time to reverse the needle when it is out of the shed than when in the latter.

Having thus described my invention it will be seen that changes and modifications may be made therein by those skilled in the art without departing from the spirit and scope of the invention and I do not wish to be limited to the details herein disclosed, but what I claim is:

1. In a weft needle operating mechanism for a loom having a warp shed, a needle rail, a needle carriage slideable along the rail toward the shed, a pair of fixed pulleys, a third pulley, a cable attached at one end to the carriage and trained around the pulleys, means to move the third pulley toward and from said pair of fixed pulleys, and means to fix the other end of the cable relatively to the axis of the third pulley and thereby cause the cable to move around the pulleys in a direction to cause the carriage to move toward the warp shed when the pair and third pulley separate relatively to each other.

2. In a weft needle operating mechanism for a loom having a warp shed, a needle rail, a needle carriage slideable along the rail toward the shed, a pair of stationary pulleys, a movable pulley, a cable attached at one end to the carriage and trained around the pulleys and having the other end thereof fixed with respect to the axis of the movable pulley, and means to move the movable pulley away from the stationary pulley to cause the cable to move around the pulleys and effect motion of the carriage toward the shed.

3. In a weft needle operating mechanism for a loom, a needle rail, a needle carriage to slide along the rail, a cable having the intermediate parts thereof attached to the carriage and having the ends thereof fixed with respect to each other, spaced stationary pulleys around which extend the parts of the cable leading from the carriage, movable pulleys between the stationary pulleys, the cable having parts extending from the stationary pulleys to and around the movable pulleys, and means to reciprocate the movable pulleys in unison in a direction toward and from the stationary pulleys to cause the carriage to reciprocate along the rail, the ends of the cable moving with the movable pulleys.

4. In a weft needle operating mechanism for a loom, a needle rail, a needle carriage to slide along the rail, two spaced sets of stationary pulleys, two sets of movable pulleys mounted to move in unison, a cable attached at an intermediate point thereof to the carriage, one end of the cable extending from the carriage being trained around one set of stationary pulleys and one set of movable pulleys, the other end of the cable extending from the carriage being trained around the other set of stationary pulleys and other set of movable pulleys, a lever on which the movable pulleys are mounted, a pair of links on which the lever is floated arranged to cause the movable pulleys to move in a substantially straight line when the lever moves, means to reciprocate the lever, and means to hold the ends of the cable fixed with respect to each other.

5. In a weft needle operating mechanism for a loom, a needle rail, a needle carriage to slide along the rail, two spaced sets of stationary pulleys, two sets of movable pulleys mounted to move in unison, a cable attached at an intermediate point thereof to the carriage, one end of the cable extending from the carriage being trained around one set of stationary pulleys and one set of movable pulleys, the other end of the cable extending from the carriage being trained around the other set of stationary pulleys, and the other set of movable pulleys, a lever on which the movable pulleys are mounted, a revolving shaft having a rotation for each pick of the loom, connections between the shaft and lever to reciprocate the latter as the shaft rotates, and means to hold the ends of the cable fixed with respect to the movable pulleys.

6. In a weft needle operating mechanism for a loom having a warp shed, a needle rail, a needle carriage to reciprocate along the rail toward and from the warp shed, a cable having the intermediate part thereof attached to the carriage, spaced end pulleys around which extend the parts of the cable leading from the needle carriage, intermediate pulleys between the stationary pulleys, the cable having parts extending from the end pulleys to and around the intermediate pulleys, means to cause reciprocating movements of the intermediate pulleys between the end pulleys and reverse the direction of relative reciprocation at two different rates, one of which is relatively slow when the needle carriage is remote from the warp shed and the other of which is relatively fast when the needle carriage is adjacent the shed, and means to cause the ends of the cable to move with the intermediate pulleys to cause the cable to turn around the pulleys and reciprocate the needle carriage along the rail when the intermediate pulleys have reciprocating movements between the end pulleys.

7. In a weft needle mechanism for an Axminster loom, an elongated needle rail extending laterally from the fabric being woven, a needle carriage to be reciprocated along the rail, a weft needle supported by and moving with the carriage, a cable having the intermediate parts thereof attached to the carriage, a set of stationary pulleys arranged transversely of the needle rail, movable pulleys rotatable about an axis transverse of the needle rail and spaced from each other in a direction transverse of said rail, certain of said movable pulleys being farther from the needle rail than other of the movable pulleys, a part of the cable leading from one side of the carriage being trained around certain of the stationary and movable pulleys and the other part of the cable leading from the other side of the carriage being trained around certain other of the stationary and movable pulleys, certain of the stationary pulleys being mounted to rotate in oblique plane so that the tops of said pulleys are at a distance from said needle rail different from the distance of the bottoms of said pulleys from the needle rail, the strands of the cables extending from the oblique pulleys toward the movable pulleys passing around different movable pulleys and the angle of inclination of the oblique pulleys being such as to cause said strands to be substantially parallel, means to cause reciprocating movement of the movable pulleys with respect to the stationary pulleys, and an anchorage for the cable ends to cause said ends to maintain the same relative position with respect to each other during the reciprocating movements of the movable pulleys.

8. In a weft needle operating mechanism for an Axminster loom, a needle rail, a needle carriage to be reciprocated along the rail, a weft needle secured to and moving with the carriage, two spaced sets of stationary pulleys, two sets of movable pulleys mounted to move in unison, a cable attached at an intermediate point thereof to the carriage, one end of the cable extending from the carriage and being trained around one set of stationary pulleys and one set of movable pulleys, the other end of the cable extending from the carriage and being trained around the other set of stationary pulleys and the other set of movable pulleys, a lever on which the

movable pulleys are mounted, a revolving crank, a link connecting the crank to the lever to move the latter generally in the direction of a line connecting the stationary pulleys, a second link pivoted to the lever and extending upwardly therefrom, a pivotal support for the upper end of the second link, a third link having one end movable about a fixed pivot, and means to attach the other end of the third link to the lever at a plurality of distances from the point of connection between the lever and the first named link which is connected to the crank, the crank causing reciprocation of the lever and means to hold the ends of the cable fixed with respect to each other.

9. In a weft needle operating mechanism for an Axminster loom, a needle rail extending from one side of the loom, a needle carriage to be reciprocated along the rail, an inner bracket adjacent to the loom secured to and extending transversely of the needle rail, a second bracket secured to and extending transversely of the needle rail adjacent the outer end of the latter remote from the loom, a longitudinally extending member secured to the brackets and spaced from the needle rail, said needle rail, brackets and longitudinally extending member constituting a rectangular frame, stationary pulleys supported at the ends of said rectangular frame, a cable having an intermediate part thereof connected to the needle carriage and having those parts thereof extending away from the needle carriage trained around the stationary pulleys, a set of movable pulleys located substantially within said rectangular frame, means to reciprocate said pulleys toward and from the stationary pulleys, the cable extending from the stationary pulleys to and around the movable pulleys, and means to hold the ends of the cable in substantially fixed relation with respect to each other, movement of the set of movable pulleys causing movement of the cable to effect reciprocation of the needle carriage along the needle rail.

10. In a weft needle operating mechanism for an Axminster loom having a needle carriage to be reciprocated toward and from the warp shed of the loom, a fixed needle rail extending laterally from one side of the loom, a fixed longitudinally extending member substantially parallel to the rail and spaced from the latter, a pair of brackets to connect the rail and the member, one of said brackets being located adjacent to the loom at one end of the rail and the other bracket being located at the outer end of the rail remote from the loom, said rail, member and brackets constituting a rectangular frame fixed with respect to the loom, a stationary pulley supported by one of the brackets and located substantially within said frame, a second stationary pulley supported by the other bracket and located substantially within said frame, a set of movable pulleys located between said brackets, means to move said set of movable pulleys toward and from the stationary pulleys, a cable having an intermediate part thereof connected to the needle carriage, one part of the cable extending away from the carriage to be trained around one of said stationary pulleys and then to one of the movable pulleys and the other part of the cable extending in the opposite direction away from the needle carriage to be trained around the other of the stationary pulleys and then around another of the movable pulleys, and means to hold the ends of the cable substantially fixed with respect to each other, movement of the movable pulleys

75 relatively to the fixed pulleys causing movement of the cable to effect reciprocation of the needle carriage along the needle rail.

11. In a weft needle operating mechanism for an Axminster loom having a needle rail and a needle carriage, a pair of spaced stationary pulleys, a set of movable pulleys, a cable extending from the needle carriage around the stationary pulleys and to and around the movable pulleys, the ends of the cable remote from the needle carriage being substantially fixed with respect to each other, operating means to move the movable pulleys relatively to the stationary pulleys to effect motion of the needle carriage along the needle rail, an oscillating lever forming part of said operating means and supporting the movable pulleys, the cable leading from a stationary pulley adjacent to one end of the needle rail being trained around two movable pulleys on one side of the lever and around a third pulley on the opposite side of the lever, the sum of the distances of said two pulleys from the lever being substantially equal to the distance of the third pulley from the lever.

12. In a weft needle operating mechanism for an Axminster loom having a needle rail and a needle carriage, a pair of spaced stationary pulleys, a set of movable pulleys, a cable extending from the needle carriage around the stationary pulleys and to and around the movable pulleys, the ends of the cable remote from the needle carriage being substantially fixed with respect to each other, operating means to move the movable pulleys relatively to the stationary pulleys to effect motion of the needle carriage along the needle rail, a lever forming part of said operating means and having the movable pulleys mounted thereon, said movable pulleys being arranged with their axes transverse of the cable and there being an even number of movable pulleys, the cable from a stationary pulley adjacent to one end of the needle rail being trained around two of the movable pulleys in front of a center line parallel to the needle rail dividing said movable pulleys into two equal groups and then around a third movable pulley behind said line, the sum of the distances of said two pulleys measured in front of said line being substantially equal to the distance of said third pulley measured rearwardly from said line.

13. In a weft needle operating mechanism for an Axminster loom having a needle rail and a needle carriage, a pair of spaced stationary pulleys, a set of movable pulleys, a cable extending from the needle carriage around the stationary pulleys and to and around the movable pulleys, the ends of the cable remote from the needle carriage being substantially fixed with respect to each other, operating means to move the movable pulleys relatively to the stationary pulleys to effect motion of the needle carriage along the needle rail, an oscillating lever forming part of said operating means and supporting said movable pulleys, the latter being arranged along an axis transverse of the cable and rotatable with respect to and movable with said lever, the parts of the cable extending to and around the movable pulleys from one side thereof engaging certain of the movable pulleys in such relation that the sum of the distances between those pulleys on one side of a center line transverse of said axis and dividing the movable pulleys into two groups is equal to the sum of the distances between the remainder of said pulleys and the said line located on the other side of said line.

14. In a weft needle operating mechanism for

an Axminster loom having a needle rail and a needle carriage, a pair of spaced stationary pulleys, a set of movable pulleys, a cable extending from the needle carriage around the stationary pulleys and to and around the movable pulleys, the ends of the cable remote from the needle carriage being substantially fixed with respect to each other, operating means to move the movable pulleys relatively to the stationary pulleys to effect motion of the needle carriage along the needle rail, said movable pulleys being arranged along an axis transverse of the cable and half of the movable pulleys being located on each side of a center line transverse of the axis and substantially parallel to the cable, half of said movable pulleys cooperating with portions of the cable extending toward one end of the rail and the other half of said movable pulleys cooperating with the other part of the cable extending toward the other end of the needle rail, the sum of the moments acting on said axis and on opposite sides of said center line with respect to those parts of the cable extending toward either end of the needle rail being equal.

15. In a weft needle operating mechanism for an Axminster loom having a needle rail and a needle carriage, a set of stationary pulleys located adjacent to each end of the needle rail, a

set of movable pulleys, a cable extending from the needle carriage around the stationary pulleys and to and around the movable pulleys, the ends of the cable remote from the needle carriage being substantially fixed with respect to each other, and operating means to move the movable pulleys relatively to the stationary pulleys to effect motion of the needle carriage along the needle rail, said movable pulleys being arranged along an axis transverse of the cable and half of the movable pulleys being located on each side of a center line transverse of the axis and substantially parallel to the cable, the parts of the cable extending from each end of the needle rail lying on opposite sides of said center line, the sum of the moments exerted on said axis on opposite sides of said center line by those portions of the cable extending to either side of the movable pulleys being equal substantially to the sum of the moments exerted on the opposite side of said center line, the stationary pulleys in contact with those parts of the cable extending to movable pulleys on opposite sides of said center line being mounted to rotate in oblique planes so that the tops of said oblique stationary pulleys are at a distance from the needle rail other than the distance of their bottoms from the needle rail.

OSCAR V. PAYNE.
